Primary Examiner — Marianne N Pandozzi*(74) Attorney, Agent, or Firm* — Lowenstein Sandler LLP(57) **CLAIM**

The ornamental design for a pour over coffee apparatus, as shown and described.

DESCRIPTION

FIG. 1 is a front perspective view of a pour over coffee apparatus showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of a pour over coffee apparatus in assembled position showing the claimed design;

FIG. 9 is a bottom perspective view thereof;

FIG. 10 is a front view thereof;

FIG. 11 is a rear view thereof;

FIG. 12 is a left side view thereof;

FIG. 13 is a right side view thereof;

FIG. 14 is a top view thereof; and,

FIG. 15 is a bottom view thereof.

The broken lines in the figures shown portions of the pour over coffee apparatus that form no part of the claimed design.

1 Claim, 13 Drawing Sheets(56)
